ELECTRIC CONNECTOR

John Felke, Chicago, Ill.

Application April 20, 1940, Serial No. 330,796

1 Claim. (Cl. 200—115.5)

This invention relates to new and useful improvements in electric connectors and more particularly to an electric cord plug.

The principal object of the present invention is to provide an electric plug of the character stated constructed in such a manner as to contain fuses for the electric circuit in which it is connected.

Another important object of the invention is to provide an electric plug of the fuse element type wherein fuse elements can be removed and replaced whenever desired.

These and other objects and advantages of the invention will become apparent to the reader of the following specification.

In the drawings:

Figure 1 represents a side elevational view of the plug.

Figure 2 is a side elevational view showing the sections thereof in separated relation.

Figure 3 is an elevational view looking at the prong end of the plug.

Figure 4 is a longitudinal sectional view through the plug.

Figure 5 is a section on the line 5—5 of Figure 4.

Figure 6 is a top plan view of the fuse containing section of the plug.

Figure 7 is an inside elevational view of the cap section of the plug.

Figure 8 is a perspective view of one of the fuse elements.

Figure 9 is a cross section taken substantially on the line 9—9 of Figure 4.

Referring to the drawings wherein like numerals designate like parts, it can be seen that the plug consists of the fuse containing section 5 and the cap section 6. The upper portion of the section 5, as shown in Figure 4, is reduced to define a shoulder 7 over which is slipped the apron portion 8 of the cap section 6.

The section 5 has a pair of pockets 9 therein for containing the fuse elements 10 (see Figure 8). Inlaid in the bottom of the section 5 are arcuate-shaped metallic members 11—11 against which the adjacent ends of the fuses 10 abut as shown in Figure 4. Each of these arcuate members is secured to the section 5 by a screw 12 at one of its ends while its opposite end is provided with an elongated outstanding connector prong 13. These prongs are disposed in spaced parallel relation as suggested in Figures 3 and 4.

As shown in Figure 6, the remaining ends of the pockets 9 are closed by the substantially circular shaped members 14 of current con-

ducting material which have the arcuate-shaped tail portions 14 inlaid in the top portion of the section 5. These arcuate-shaped tail portions are secured to the section 5 by screws 15, while at the screw secured end of the tail members 14 are the upstanding flanged lugs 16 which are adapted to be engaged by the depending hook members 17 on the inside of the cap 6. As shown in Figure 7, these hook members 17 which are of current conducting material are carried by arcuate-shaped conductor strips 18, each being secured in place to the cap 6 by a binding screw 19.

A cord 20 with its conductors 21 is disposed through an opening 22 in the cap 6 and the conductors 21 are secured by the binding screws 19.

It is a simple matter to partly rotate the cap to disconnect the hooks 17 from the lugs 16 for the purpose of renewing the fuses 10 or properly connecting the conductors 21 with the binding screws 19.

It is preferable that the periphery of the cap 6 be knurled or milled as denoted by numeral 23 to facilitate turning thereof.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

An electric connector comprising a body, a cap structure for the body, said body being rabbeded at one end to define a shoulder against which the cap engages, a pair of contact strips on the rabbed end of the body, each of said strips having one end anchored to the body and its other end offset from the body, said cap having a pair of contact members of elongated construction at the inner side thereof, each of the said elongated contact members having one end anchored to the cap and its other end offset, said cap structure being rotatable on the shoulder of the body to bring the offset end portions of the contacts of the cap into interlapping engagement with the offset end portions of the contact on the body, said body being provided with a pair of openings therethrough, a fuse in each of the openings, a pair of prongs projecting from the remaining end of the body and having the fuses bearing against the inner ends thereof, the contact on the body being in contact with adjacent end of the fuses.

JOHN FELKE.
